CLAIM

The ornamental design for a sling adapter, as shown and described.

DESCRIPTION

FIG. 1 is a right, top, front perspective view of a sling adapter attached to a firearm showing my new design;
FIG. 2 is a left, front, top perspective view of the sling adapter.

FIG. 2 is a left, front, top perspective view of the sling adapter of FIG. 1 with the firearm omitted;
FIG. 3 is a left side elevation view of the sling adapter of FIG. 1, the right side elevation being a mirror image;

FIG. 4 is a top plan view of the sling adapter of FIG. 1; and FIG. 5 is a bottom plan view of the sling adapter of FIG. 1. FIG. 6 is a front elevation view of the sling adapter of FIG. 1, the right side elevation being a mirror image;

FIG. 6 is a front elevation view of the sling adapter of FIG. 1; and,
FIG. 7 is a rear elevation view of the sling adapter of FIG. 1. The broken lines showing portions of the design in all figures is included for the purpose of illustrating environment and unclaimed features and forms not part of the claimed design.
